(57) **CLAIM**

The ornamental design for a surgical cement tapping tool, as shown and described.

DESCRIPTION

FIG. 1 is a perspective view of a surgical cement tapping tool in accordance with the new design;

FIG. 2 is an enlarged partial right side view of the surgical cement tapping tool of FIG. 1;

FIG. 3 is an enlarged partial left side view of the surgical cement tapping tool of FIG. 1;

FIG. 4 is an enlarged partial top view of the surgical cement tapping tool of FIG. 1;

FIG. 5 is an enlarged partial bottom view of the surgical cement tapping tool of FIG. 1;

FIG. 6 is a front view of the surgical cement tapping tool of FIG. 1; and,

FIG. 7 is a rear view of the surgical cement tapping tool of FIG. 1.

In the drawings, the broken lines shown in FIGS. 1, 6 and 7 illustrate portions of the surgical cement tapping tool that form no part of the claimed design.

1 Claim, 6 Drawing Sheets
